POURING SPOUT CONSTRUCTION

Otto M. Miller, Jr., Hillsdale, N.J., assignor to Continental Can Company, Inc., New York, N.Y., a corporation of New York

Filed Sept. 22, 1958, Ser. No. 762,323

3 Claims. (Cl. 229—17)

The invention relates to a pouring spout construction for a paperboard carton, and especially to a construction which prevents the attachment of the lifting tab to the panel which underlies the same.

Summary

I have discovered an improved pouring spout construction which solves the problem of accidental securing of the free lifting tab to the panel underlying it during the carton setting up operation. According to my invention it is possible to form a pouring spout from two attached overlapping panels while still maintaining a cut out portion of the outer panel free from any attachment to the inner panel so that it may act as a convenient lifting tab for opening the spout.

My invention consists of an improved pouring spout construction for a paperboard carton which has one of its walls formed by two panels which overlap at least partially. In such a carton the pouring spout construction includes a spout forming flap in the underlying portion of the inner panel, which flap is defined by interrupted cut lines so that it may be readily separated from the remainder of the inner flap. Overlapping this spout forming flap and secured thereto is a closure flap formed from the outer panel. A portion of the closure flap extends beyond the extremity of the spout forming flap to overlie a part of the inner panel and form a lifting tab so that when the tab is lifted the spout forming flap and closure flap are pulled away from the carton wall to leave an opening. In order to prevent the accidental securing of this lifting tab to the portion of the inner panel which it overlies and in order to facilitate the gripping of the lifting tab, I provide a ridge on either the lifting tab or the portion underlying it, or both, to keep the major portion of these parts spaced from each other both when the carton is being set up and after it has been set up.

Other objects and advantages will appear as the description proceeds.

Description

In the drawings wherein I have illustrated the best mode contemplated by me of carrying out my invention:

Fig. 1 is a perspective view of a carton embodying my invention with the pouring spout construction being shown in closed position;

Fig. 2 is a perspective view of the portion of the carton of Fig. 1 which forms the pouring spout with said pouring spout being shown in opened position;

Fig. 3 is a view similar to Fig. 2 showing the spout forming flap and the closure flap before they are secured together; and

Fig. 4 is a cross-sectional view showing the pouring spout construction when in closed position, said view being taken along the line 4—4 of Fig. 1 looking in the direction of the arrows.

Referring to the drawings, I will now describe a paper-

2

board carton embodying the pouring spout construction of my invention in one of its preferred forms.

The carton is generally rectangular and is completely closed at its ends. One of the sides includes two panels, 5 10 and 11, which overlap, at least in part. The outer panel 10 forms the exterior side of the carton. A spout forming flap 12, near the top edge of this side wall, is cut out of inner panel 11 along top and bottom cut lines 13 and 14, respectively, and along interrupted side cut lines 10 15 and 16. Cut lines 15 and 16 hold flap 12 in a position coplanar with panel 11 until flap 12 is pulled away and the small uncut portions joining flap 12 and panel 11 are torn. Cut out along cut line 18, from outer panel 10 is a hinged closure flap 17, a portion of which is secured to flap 12, as by a suitable adhesive shown at 19 in the drawings. Part of the portion or lifting tab 20 of flap 17 which extends beyond the edge of flap 12 to overlie flap 11 is cut off so as to leave part of panel 11 exposed when the spout construction is in closed position. As is evident, 15 in order to form the spout or opening communicating with the interior of the carton, the lifting tab 20 is grasped and pulled upwardly and outwardly from the side wall, thereby pulling flap 17 upwardly and outwardly and tearing flap 12 loose from panel 11. In order to 20 reclose the carton, flap 17 is pushed downwardly and inwardly until the sides of flap 12 frictionally engage the sides of the spout or opening.

In a carton of the type described, it has been found that tab 20 has a tendency to become adhesively secured 30 to the portion of panel 11 which underlies it. This is true, in part, due to the fact that the adhesive is applied to flap 12 by a roller which also deposits some glue on this underlying portion of panel 11. In accordance with my invention, this problem is solved by the formation of 35 at least one score line 22, on the outer surface of the tab or the inner surface of the portion underlying it, or both, so as to form a raised ridge portion 21 on at least one of the facing surfaces. The preferred form, shown in the drawings, includes a pair of spaced, parallel, longitudinally extending ridge portions on the inner face of tab 20 and a pair of spaced, parallel, longitudinally extending ridge portions on the outer face of the underlying portion of panel 11. The ridges on the two surfaces are in alignment, as best seen in Fig. 4, when the flaps 12 and 17 40 are in closed position.

It is clear from the drawings that the practicing of my invention eliminates the possibility of tab 20 becoming firmly secured to the underlying portion of panel 11 since any excess adhesive applied by the roller during the 50 carton set-up operation will lie between the ridges 21 on panel 11 and will not contact tab 20. Should some adhesive be inadvertently applied to the ridges 21, the tab 20 may still be easily moved since the tab will be secured to only the ridges along a very small line of contact which 55 may readily be broken. The spacing between tab 20 and the portion of panel 11 underlying it also facilitates the grasping of tab 20 with a finger or suitable implement. In order to further facilitate such grasping, tab 20 can be 60 separated from flap 17, to which it is connected, by a score line 23.

The terms and expressions which I have employed are used in a descriptive and not a limiting sense, and I have no intention of excluding such equivalents of the invention described as fall within the scope of the claims.

65 I claim:

1. In a hinged pouring spout construction for a paperboard carton having one wall formed by two panels which overlap at least partially, in which said construction includes a spout forming flap in the underlying portion 70 of the inner panel and defined by interrupted cut lines so that it may be readily separated from said underlying portion, and a closure flap in the outer panel in over-

lapped relation to the spout forming flap and secured thereto, as by an adhesive, said closure flap having a tab connected thereto which extends beyond the corresponding extremity of said spout forming flap and overlies part of said inner panel; the improvement comprising a raised ridge on the contacting surface of said tab and a raised ridge on said part of said inner panel underlying the tab, the two raised ridges being in alignment when the tab is in a position overlying said part of the inner panel, thereby maintaining a space between said contacting surfaces to prevent accidental securing together over a relatively large area of said contacting surfaces when the spout forming flap and the closure flap are secured together, said spacing also serving to facilitate the grasping of the tab by a person desiring to open the pouring spout by tearing loose the portion of the spout forming flap which is still attached to the inner panel.

2. A lift up spout forming construction for a paper-board carton having a fixed panel and a free lifting tab overlying a portion of said fixed panel and being spaced

therefrom by a raised ridge on the portion of said fixed panel underlying said lifting tab, and a raised ridge on the portion of said lifting tab overlying said fixed panel, said raised ridges being aligned when the tab is in a position overlying said fixed panel, said spacing preventing the accidental securing of the major portion of the tab to said panel and also facilitating the lifting of the tab away from said panel.

10 3. A pouring spout construction in accordance with claim 1, and wherein said aligned ridge portions extend longitudinally, and further comprising a second set of aligned longitudinally extending ridge portions on said contacting portions parallel to and spaced from said first set of aligned ridges.
